UNITED STATES PATENT OFFICE.

WALTER OTTO EICHENBERGER, OF GRAY, SASKATCHEWAN, CANADA.

GRAIN-SHOCKING MACHINE.

Application filed December 9, 1918. Serial No. 265,943.

To all whom it may concern:

Be it known that I, WALTER OTTO EICHENBERGER, a citizen of the United States, residing at Gray, Province of Saskatchewan, Canada, have invented certain new and useful Improvements in Grain-Shocking Machines; and I do hereby declare that the following is a full, clear, and exact description of the invention, such as will enable others skilled in the art to which it appertains to make and use the same.

The present invention relates to machines for shocking grain, and an object of the present invention is to provide a machine of this character which will catch the sheaves as they are delivered from the binders and set the sheaves in shocks upon the ground.

With the above and other objects in view which will hereinafter appear as the description continues, the invention consists of the novel features of construction, combination and formation of parts as will be hereinafter more fully described and particularly pointed out in the appended claims.

In the accompanying drawings has been shown a simple and preferred form of the invention, it being, however, understood that no limitation is necessarily made to the precise structural details herein exhibited, but the right is hereby reserved to any changes, alterations or modifications to which recourse may be had that come within the scope of the claims without departing from the spirit of the invention or sacrificing the efficiency of the same.

In the accompanying drawings:

Figure 1 is a side elevation of the machine embodying the present invention;

Figure 2 is a plan view of the same;

Figure 3 is a vertical transverse section taken on the line 3—3 of Figure 2;

Figure 4 is a detail sectional view of the clutch when in one position;

Figure 5 is a detail view of the clutch when in another position;

Figure 6 is a detail section of the connection through the clutch operating means;

Figure 7 is a detail side elevation of the finger actuating means;

Figure 8 is a detail transverse section of the same;

Figure 9 is a detail side elevation of the finger actuating means;

Figure 10 is a plan view of the same;

Figure 11 is a detail view of the finger supporting rods;

Figure 12 is a detail plan view of the slideable platform;

Figure 13 is a detail section through the same; and,

Figure 14 is a detail perspective view of one of the connecting clamps;

Figure 15 is an enlarged detail of the mechanism connecting the forked frame to the cable 50.

Referring now more particularly to the accompanying drawings wherein like and corresponding parts are designated by similar reference characters throughout the several views,

The machine embodying the present invention is adapted to be secured to one side of an ordinary binder, so that as the binder is propelled over the ground the shocking machine will be carried therewith. This machine comprises a frame work 1 of substantially a squared configuration and will be suitably connected to the side of an ordinary binder. The forward end of this frame is provided with a diagonally extending bar 2 which may be connected to the stub tongue of the binder through the pivotally connected clamp 3, so as to overcome any side draught when the machine has been drawn over the ground. Journaled within the frame is an axle 4 carrying a ground wheel 5 and connected to this axle is a sprocket wheel 6, which through a sprocket chain 7 is connected to a smaller sprocket wheel 8 and the latter being loosely mounted upon the transversely extending shaft 9. A shaft 10 parallel to the shaft 9 is also journaled within the frame 1 and these shafts are operatively connected through the sprocket chain connection 11. Keyed to the shaft 9 but slidably mounted thereupon is a sleeve 12 having one member of a clutch formed therewith which is adapted to engage the other member of the clutch carried by the sprocket wheel 8. A coil spring 13 normally holds these clutch members into engagement, so that when the machine is being drawn over the ground the wheel 5 will rotate thereby transmitting a rotary motion to the shafts 9 and 10 in the direction of the arrows as shown. For holding the clutch members out of engagement I provide a clutch actuating means which comprises a forked arm 14 which engages the sleeve 12 and this arm 14 has one end connected to a lever 15 and the latter is pivotally connected to the frame 1. When a pull

is exerted upon this lever 15, as better illustrated in Figure 4, the clutch members will be held out of engagement, but when this lever 15 is released the coil spring 13 will 5 force the clutch members into engagement. Suitably supported within the frame work of the machine are the vertical shafts 16 and 17, which through a suitable gearing (not shown) are connected to the respective shafts 10 and 9. Also suitably journaled within the frame 1 are the vertical shafts 18. These shafts 16, 17 and 18 are provided with suitable sprocket wheels 19 over which pass the endless belts 20 and the latter are provided 15 with the projections 21. From this construction it is obvious that when the shafts 9 and 10 are set in motion the belts 20 will also be set in motion and caused to travel in the direction of the arrows as shown in Figure 2. Also suitably journaled within the frame 1 are the vertical shafts 22 and 23 which are connected to the respective shafts 16 and 17 through the sprocket chain connections 24. Horizontally journaled 20 within the frame 1 is a roller 25 and a suitable endless conveyor 26 passes over this roller 25 and a similar roller carried by the vertical shaft 23. Supported upon the frame 1 are the bearing blocks 27 having journaled 25 in their upper ends a roller 28 and an endless conveyor 29 extends over this roller 28 and a similar roller carried by the vertical shaft 22. When the shafts 9 and 10 are set 30 in motion the conveyors 26 and 29 will also be set in motion. The outer ends of these conveyors 26 and 29 are arranged adjacent to the binder, so that as the sheaves leave the binder they will drop upon the conveyor 26 in a horizontal position. As this conveyor 35 26 is set in motion it will carry the sheaves along until they have been set up in a vertical position between the endless carriers 20. The conveyor 26 acts as a support for the sheaves, whereas the conveyor 29 guides 40 the sheaves as they are carried along and causes the same to be set up in a vertical position between the carriers 20. These carriers 20 carry the sheaves along in a vertical position and finally deposit the same upon 45 the movable platform 30 of the shock former. This movable platform of the shock former comprises a plate 31 which is slidably mounted in a longitudinal direction within the grooves formed within the bars 32. One 50 end of this plate is connected by the coil springs 33 to the outer ends of the bars 32, whereby the plate will normally assume the position as better shown in Figure 1. Connected to the opposite end of this plate is a 55 cable 34 and this cable has one end connected to a crank lever 35 mounted upon the shaft 36. This shaft 36 extends transversely of the frame 1 and has one end terminating adjacent the driver's seat arranged upon the 60 binder. A lever (not shown) may be con-

nected to this shaft 36 for revolving the same, so that as this shaft is rotated the cable 34 will be wound thereupon whereby the movable platform or plate 31 can be drawn under the platform 37 mounted upon the frame 1. When this plate 31 is drawn inwardly the conveyors should be stopped and in so stopping these conveyors it is necessary to disconnect the shaft 9 from the ground wheel 5. Slidably mounted upon the cable 34 and adapted to frictionally engage the same is a sleeve 38 and the latter is connected by means of a cable 39 to the lever 15. When this cable is drawn in the direction of the arrow as better shown in Figure 4, whereby the plate 31 will be drawn beneath the frame of the machine, the clutch members will be separated thereby disconnecting the power to the shaft 9, but when this cable 34 is released it will assume the position as better shown in Figure 5 whereby the clutch members will engage and the conveyors again set in motion. When a pull is exerted upon the cable 34 in the direction of the arrow as shown in Figure 4, the lever 15 will be operated so as to separate the clutch members, but if it is required to pull the cable a considerable distance the cable 34 will slide within the sleeve 38 but will still retain the clutch members out of engagement. When the cable 34 has been released the spring 13 will cause the sleeve 38 to assume the position as shown in Figure 5.

Mounted within suitable bearings carried by the frame 1 are a pair of vertical shafts 40 each of which has connected thereto the segmental fingers or arms 41. A coil spring 42 connects each of these shafts 40 with the frame 1, whereby the arms 41 will be normally held in the position as illustrated in Figure 2. Pivotaly mounted as at 43 upon the frame 1 is a forked frame 44. When the sheaves leave the endless belts 20 they are deposited upon the plate 31 and when between eight and twelve of these sheaves have been placed upon the plate 31 they will form a shock and this shock of sheaves is retained upon this plate by means of the arms 41. In releasing this shock of sheaves the plate 31 is drawn under the platform 37 and the sheaves will then drop upon the forked frame 44 from which they are deposited upon the ground. The weight of the sheaves causes this forked frame 44 to swing down on its connection and when the sheaves are being placed upon the ground the fingers or arms 41 should be released. Supported upon the frame 1 is an inverted U-shaped bar 45 and slidably mounted upon this bar is a pair of blocks 46. Each of these blocks has journaled thereupon a grooved roller 47 which travels within the slots 48 formed within the frame 49 carried by the shafts 40 and the arms 41. Connected to each block 46 is a cable 50 which cable

passes over the rollers 51 journaled within the bar 45 and these cables 50 are connected to the levers 52. One end of each of these levers 52 is connected to the forked frame 5 44 and their opposite ends are provided with the grooved rollers 53 which ride upon the bar 45. As the forked frame 44 is lowered a pull will be exerted upon the cables 50 thereby drawing the blocks 46 upon the 10 frame 45. As the rollers 47 are carried with these blocks they will be forced to travel through the slots 48, thereby swinging the arms 41 outwardly for releasing the shock.

15 From the foregoing it is obvious that as the machine is being propelled over the ground the sheaves from the binder will be deposited upon the conveyor 26. This conveyor being set in motion will cause the 20 sheaves to be set in a vertical position between the carriers 20 and these carriers will finally deposit the sheaves upon the plate 31 until a shock is formed upon this plate. The arms 41 will encircle the sheaves and 25 hold the same in position. When the required number of sheaves has been deposited upon the plate 31, the operator seated upon the binder will revolve the shaft 36 which in turn will exert a pull upon the cable 34 thereby drawing the plate 31 from below the sheaves, permitting the sheaves to drop upon the forked frame 44. As a pull is exerted upon this cable 34 the shaft 9 will be disconnected from the ground wheel 5 and the conveyors 20, 26 and 29 will be 30 stopped. The weight of the sheaves upon the forked frame 44 will cause the latter to swing upon its pivoted connections 43 and by the movement, the arms 41 will be swung 35 outwardly to release the sheaves through the mechanism as formerly described. The sheaves are then deposited upon the ground in shocks. As the sheaves are released from the forked frame 44 they will assume an upright position and the arms 41 will be returned to their position as shown in Figure 40 2, due to the fact that the shafts 40 are under tension by means of the coil springs 42. The shaft 36 is then released and the coil 45 springs 33 will cause the plate 31 to return to its normal position or that shown in Figure 2. When this shaft 36 is released the

cable 34 will also be released, thereby permitting the clutch members to engage whereby the ground wheel 5 will again be 55 connected to the shaft 9 and the conveyors again set in motion so as to form the next shock.

Having thus fully described my invention, what I claim as new and desire to secure by Letters Patent is:

1. A grain shocking machine of the character described comprising a wheeled frame, a sliding plate supported on said frame, conveyors on said frame leading to said plate, vertical shafts positioned adjacent said plate and conveyors, arms on said shaft for retaining shocks of grain on the plate, a movable forked frame, means for normally retaining said plate above said forked frame, means for sliding said plate whereby the shocks supported thereby may be deposited upon said forked frame, and means operatively connecting said forked frame with said arms whereby the arms will release said grain shocks when the latter have been deposited upon said forked frame.

2. In a grain shocking machine, a wheeled frame, a plate slidably mounted upon said wheeled frame, means for moving said plate 80 longitudinally thereon, opposed horizontally movable arms pivotally mounted on the frame adjacent to the plate, conveyors on the frame leading to said plate, a tiltable forked frame mounted on the wheeled frame 85 directly below said plate, slotted frames fixedly secured to the horizontal arms, an inverted U-shaped frame on the wheeled frame and adjacent to the plate, rollers slidably mounted on the horizontal portion of 90 the U-shaped frame, and arms pivotally connected to said forked frame and slidably engaging the vertical portion of the U-shaped frame and having connection with said rollers whereby upon downward movement of said forked frame, the rollers are 95 carried along said horizontal portion of the U-shaped frame, thus pulling the slotted frame and the horizontally movable arms outwardly with respect to the plate.

100 In witness whereof I have hereunto set my hand.

WALTER OTTO EICHENBERGER.
